CLAIM

The ornamental design for a breathing apparatus display screen with graphical user interface, as shown and described.

DESCRIPTION

FIG. 1 is a front view of a breathing apparatus display screen with graphical user interface for a display screen or portion thereof;

FIG. 2 is a front view of the breathing apparatus display screen with graphical user interface of FIG. 1 in an alternate unclaimed environment; and,

FIG. 3 is a front view of the breathing apparatus display screen with graphical user interface of FIG. 1 in a second alternate unclaimed environment.

The broken lines in the Figures showing a display screen or portion thereof, text, and other elements form no part of the claimed design.

1 Claim, 3 Drawing Sheets
